UNITED STATES PATENT OFFICE

VICTOR SCHLEYER, OF ANDERSON, INDIANA

TURBO PUMP

Application filed January 10, 1927. Serial No. 160,198.

It is the object of my invention to provide a centrifugal pumping means, more especially a turbine-driven vertical-shaft water pump as for supplying boiler-feed water, which is compact and rugged in structure, is readily accessible for inspection and repair, has a main bearing which is an anti-friction bearing directly accessible from the top, and has certain advantages in construction and operation which will appear from the following specification.

In carrying out my invention in the preferred form illustrated, I provide a vertical shaft which has a main anti-friction bearing at or near its upper end, which carries a turbine rotor at an intermediate point near the upper end and the runners of one or more stages of a centrifugal pump at or near the lower end, with a steady bearing between the turbine and the pump. Above and below the turbine rotor I provide novel glands each of which has a plurality of axially loose packing rings within it; which glands I find most effective in preventing leakage, especially when the turbine exhaust is against a high back pressure. Between the upper of such glands and the main anti-friction bearing I mount on the shaft an umbrella which serves to protect the bearing in case there is leakage through such gland; and make this umbrella serve the three-fold purpose of deflecting any leakage steam through such gland, of carrying fan blades which serve both as ventilating fan blades and as blades which throw outward any steam escaping through such gland, and of carrying a centrifugally operated device which controls a trip for a throttle in the steam-supply line. The main bearing and the steady bearing are both desirably jacketed bearings for cooling in warm weather and heating in cold weather, for cooling purposes conveniently being supplied with cool water from the pump when the pump is a water pump, which cool water may be taken from between two stages of the pump if it is a multi-stage pump. I desirably make the pump such a multi-stage pump, and provide a stationary member which forms part of both stages and integrally carries diffusers for both stages. In such a multi-stage pump,

the two stages may have their suction inlets facing the same direction, desirably upward, or facing in opposite directions, as upward for the upper stage and downward for the lower stage. In either case, especially the former, I provided differential areas facing opposite axial directions on the pump runners for getting any desired balance and floating effect on the rotating element as a whole. Whether the pump is a single stage or a multi-stage pump, I provide its fluid-inlet and fluid-outlet connections in the casing in a manner which permits the removal of the pump runner or runners and the internal pump mechanism without disturbing such connection. Further, I provide in the fluid inlet for the pump, especially if the pump is used as a feed-water pump, a strainer arranged so that it will not interfere with the free flow of water and so that it can readily be removed, replaced, inspected, and cleaned without disturbing any of the fluid connections to the pump or to the source of water-supply.

The accompanying drawings illustrate my invention: Fig. 1 is a vertical central section through a turbo-pump embodying a preferred form of my invention, the section being taken substantially on the line 1—1 of Fig. 2, though with the rotating element slightly turned on its axis to show the entire centrifugal device without foreshortening; Fig. 2 is a horizontal section substantially on the line 2—2 of Fig. 1; Fig. 3 is a vertical section substantially on the line 3—3 of Fig. 1; Fig. 4 is a disassembled view of the parts constituting the lower portion of Fig. 1, to show how they can be removed and replaced; Fig. 5 is a fragmental sectional view generally similar to the lower part of Fig. 1, but showing a modification in which the two stages of a two-stage pump are arranged back to back, with the inlet of the first stage opening upward and the inlet of the second stage opening downward, the section being taken on the line 5—5 of Figs. 6 and 7; and Figs. 6 and 7 are fragmental sections on the lines 6—6 and 7—7 respectively of Fig. 5, to show the arrangement of the diffusers of the two stages of the pump and the associated passages thereof.

The vertical shaft 10 carries all the rotating parts both of the prime mover, which is here specifically a steam turbine, and of the centrifugal pump, which is here a liquid-moving pump as for pumping feed water to a boiler, such as a locomotive or marine boiler. This shaft is mounted within a casing 11, which may be composed of various parts as appears from the drawing and as will be pointed out to some extent hereafter in the description.

At its upper end, the shaft 10 is supported in a ball-bearing 15, which is the main bearing with which the shaft is provided. This ball-bearing 15 has its outer race 16 clamped in a bearing-housing-top 17 by a removable cap 18, which cap extends over the upper end of the shaft 10 and may be removed to give access to such upper end and to the ball bearing. The ball-bearing has its inner race 19 clamped in place on the shaft, (together with certain other parts later to be described,) by a nut 20 on the shaft-end just below the removable cap 18. The bearing-housing-top 17 is removably mounted on a bearing housing 21, which has an inner oil-holding chamber from which oil is circulated through the bearing by an oil flinger 22 clamped on the shaft 10 below the inner race 19 by the nut 20; and which has an outer jacket chamber 23 through which water or steam is circulated, as from a supply pipe 24 and a discharge pipe 25 connected in a manner later to be described.

35 The bearing housing 21 is mounted on top of a turbine housing 30, within which is a turbine rotor 31 of any desired construction.

The turbine housing 30 is provided with glands 32 and 33 which surround the shaft 10 above and below the turbine rotor 31.

Much difficulty was experienced from leakage through these glands when they were made as ordinary packing glands; and I have found that this leakage is almost wholly avoided, and that the life of the packing material is increased, by providing the glands with a plurality of fairly loose packing rings 34 less than sufficient to fill the gland-box, so that a pressure space 35 is left in the gland box. Any steam from the turbine casing which tends to get into the gland-boxes occupies the spaces 35; and the loose packing rings 34, which rotate generally with the shaft base at a less speed and at least at times 55 at different speeds among themselves, apparently assume positions among themselves, probably with some shifting among themselves in operation, that effectively serves to reduce leakage to a minimum. The packing

60 ring 34 farthest from the rotor 31 in each gland 32 and 33 makes an effective seal against the associated stationary gland-follower 36, which is made integral or otherwise non-rotatable relative to the gland-nut 37 65 so that the follower will not rotate with the

shaft. This construction is found to be very effective in reducing leakage of steam from the turbine around the shaft.

The turbine is shown as a single-stage turbine, having a live steam inlet nozzle 40, and a re-entrant nozzle 41; but this is merely for the sake of illustration, as the fact that the turbine is shown as a re-entrant single-stage type of turbine has nothing to do with my present invention.

70 The turbine housing 30 is provided at one side with an exhaust opening 45 opening horizontally, and at the other side with a vertically opening inlet 46 in which is mounted the nozzle head 47 which carries the nozzle 40. Above the nozzle head 47 is a throttle-valve casing 48, which receives a supply of steam from above through a pipe 49. Within this throttle-valve casing 48 is a throttle valve 50, which is shown as of the butterfly type. (See Figs. 1 and 2.) The shaft of this butterfly valve carries a latch-arm 51, which is acted on by a torsion spring 52 tending to move the butterfly valve 50 to closed position, which is the horizontal position of Fig. 1. The latch-arm 51 may co-operate with a latch finger 53 which at normal speeds holds the latch-arm 51 horizontal and the throttle valve 50 open. When the latch finger 53 is disengaged from the end of the latch-arm 51, such latch-arm is moved upward, (or counter-clockwise in Fig. 1) by the spring 52 to move the throttle valve 50 to closed position. The shaft of the throttle valve may be provided with a second arm 54, which is shown as movable between two stops 55 and 56 for the open-throttle and closed-throttle positions of the throttle valve 50; and to the end of this second arm 54 there may be attached a pull-cable 57 extending upward through a floor 58 on which the operator stands; such as the floor of the cab of a locomotive, so that by pulling upward on such cable 57 the throttle valve 50 may be moved from closed to open position and the latch-arm 51 caught by the latch finger 53.

105 The latch finger 53 is mounted on a vertical pivot 60, and has an operating finger 61 which extends substantially tangentially to the path of a centrifugally operated plunger 62 mounted in a boss 63 on the under side of an umbrella disk 64 fixed on the shaft 10 and rotatable therewith. This umbrella disk 64 may have a supporting sleeve or hub by which it is clamped in place on the shaft by the nut 20 along with the inner ball race 19 and the oil flinger 22. The plunger 62 is a radial plunger, spring-pressed inward in the lug 63 by a compression spring 65 and movable outward by centrifugal force against the action of said spring. If the speed of rotation exceeds a predetermined value, the outer end of the plunger 62 strikes the operating finger 61 and moves it to disengage the latch finger 53 from the latch arm 51, so that the spring 110

52 may close the throttle valve 50 to shut off the supply of steam to the turbine.

The umbrella disk 64 not only serves to

5 carry the plunger 62, but also serves two other purposes: First, it serves as an umbrella or deflector between the gland 32 and the ball-bearing 15; so that if any steam does escape through the gland 32, it is deflected outward by such umbrella disk 64 and pre-

10 vented from reaching the housing of the bearing or from getting into the bearing or the oil chamber thereof. Second, the umbrella disk 64 is provided on its under face with both the lug 63 and a balancing lug 66,

15 the latter lug serving to balance rotatively the lug 63 and the parts carried thereby, and both lugs serving as centrifugal fan blades which assist in throwing outward any steam escaping upward through the gland 32 and

20 also produce an air circulation which assists in cooling the entire device. To this end, that portion of the turbine housing 30 which surrounds the gland nut 37 and the umbrella disk 64 and its carried parts is made as a

25 skeleton housing.

The device as a whole may be supported by the turbine casing 30, in any convenient manner, as by having attaching lugs provided at convenient points on the periphery of 30 said turbine casing. I have shown only one attaching lug 68, but there may be any desired number.

Below the turbine housing 30 are successively an intermediate housing 70 and a pump

35 housing 71. The intermediate housing 70 furnishes a support for a steady bearing 72, which is a plain bearing screw-mounted in an internal boss 74 provided on an intermediate housing 70. The bearing 72 has the

40 usual gland 75 at its upper end, and may be provided with any lubricant-supply means, such as a grease cup 76. The plain bearing 72 is desirably provided with a jacket chamber 77, having a completely open periphery

45 at an intermediate height to communicate with a water-supply passage 78 provided in the internal boss 74; and at its lower end has water-outlet openings 79 which communicate with a main water-inlet passage 80 provided

50 in the intermediate housing 70. This main water-inlet passage 80 also supplies water for assisting in lubricating the bearing surfaces of the steady bearing 72; for facilitating

55 which water lubrication, which is partly by capillarity and partly by gravity, the water-inlet passage has its inlet end elevated so that the normal water level in such passage will stand higher than the lower end of the steady bearing.

60 The main water-inlet passage 80 communicates with the upwardly opening inlet eye 83 of the centrifugal pump, which is located

65 at the lower end of the shaft 10, so that the steady bearing 72 lies between the pump and the turbine. The pump may consist of any

desired number of stages, but is desirably a two-stage pump having two rotors 84 and 85 fixed on the shaft 10 at different levels. Removably mounted in the pump casing 71 is a diffuser body 86, which has diffuser vanes 70 87 and 88 both of one piece with the diffuser body 86, so that there is a plane of separation at the top of the upper diffuser vanes 87 and at the bottom of the lower diffuser vanes 88, between the diffuser body 86 and the intermediate casing 70 and between the diffuser body and a bottom cap-plate 89 respectively. The bottom cap-plate 89 covers the lower end of the shaft 10.

This construction permits ready inspection and removal of the parts in the manner shown in Fig. 4. The lower cap-plate 89 may be removed to give access to the lower runner 85, and to the passages between the lower diffuser vanes 88, as well as to the passages (to be described) through such diffusers in the modification shown in Figs. 5, 6, and 7. This permits the removal of the lower runner 85, then of the diffuser 86, and then of the upper runner 84. By making the diffuser 80 vanes 87 and 88 integral with the diffuser body 86, manufacture and assembly are facilitated; for the lower face of the intermediate housing 70 and the upper face of the lower cap-plate 89, which are the end-plates 95 of the pump, may both be made as flat machined surfaces where they co-operate with the edges of the adjacent diffuser vanes. The passages between the lower diffuser vanes 88 open into an involute discharge 90 chamber 90 communicating with a water-discharge pipe 91.

The pipe 91 and the water supply passage 78 for supplying water to the jacket chambers of the main bearing 15 and steady bearing 52 may be connected to the discharge of the first stage of the pump, as is indicated in Fig. 1; and the pipe 25, as well as the water-outlet openings 79, may discharge into the main water-inlet passage 80.

The two pump runners 83 and 84 may both have their suction eyes opening upwardly, as shown in Fig. 1. In that case, the diffuser body 86 has passages 93 which carry the water discharged from between the upper diffuser vanes 87 inward to the inlet point of the runner 85. With this construction, in which both stages of the pump have their inlets opening upward, there is a substantial tendency to lift the whole rotating unit upward in operation. This tendency is counteracted as follows: Wearing or sealing rings 94 are provided on each side of each pump runner, which rings rotate with the runner and are received in annular grooves 105 in co-operating stationary wearing or sealing rings mounted in the stator of the pump.

The diameters of the different sealing rings 94 may have any desired relation, to produce any desired relation between the areas of 110

the upper and lower surfaces of the two runners outward from their respective wearing rings, and thus to produce any desired resultant thrust on the shaft 10 by the reaction of the water under pressure on such exposed portions of the upper and lower surfaces of the two pump runners. This will be apparent from the fact that the different rings 94 are shown as of different diameters. The resultant pressure or thrust referred to is in proportion to the algebraic sum of the upper and lower runner-faces, one being considered as positive and the other as negative; and while this resultant may be made anything desired, the combined area of the exposed upper surfaces of the two pump runners is made slightly greater than the combined area of the exposed lower surfaces thereof, so that there will be a slight resultant downward thrust from the pressures on such surfaces, to compensate for the lifting tendency from having the inlets to both pump runners opening upward.

This lifting tendency may be reduced, and the necessity for the balancing or compensating thrust correspondingly reduced or even eliminated, by having the eyes of the two stages of the pump open in opposite directions. Such a construction is shown in Figs. 5, 6, and 7. In that case, the inlet eye of the upper pump runner opens upward, and the inlet eye of the lower pump runner opens downward. This requires a special arrangement of passages in the diffuser body 86, as will be clear from Figs. 6, 7, and 8. The diffuser vanes 87 of the upper stage are as shown in Fig. 6, and between adjacent upper diffuser vanes 87 the diffuser body is provided with openings 100 which leads into a circumferential chamber 101 in the diffuser body between the two pump stages. The diffuser vanes 88 of the lower pump stage are made hollow, as is best shown in Fig. 7, to provide passages 102 which lead down through such lower diffuser vanes 88 into a chamber 103 provided in the lower cap plate 89. This chamber communicates with a downwardly opening eye of the lower pump runner 83 in this modification; and such lower pump runner discharges outwardly through the spaces between the diffuser vanes 88 into the involute chamber 90. This back-to-back arrangement of the two pump stages has considerable advantage.

In many pumps, as for instance in boiler feed-water pumps, it is desirable for the sake of safety to use a strainer; to prevent solid matter from being carried into the pump. To this end, I provide the main water-inlet passage 80 as a lateral outlet from a cylindrical casing 110, shown as a horizontal casing; which casing has flanges 111 at its two ends to receive cap-plates 112 and 113 which clamp between them a cylindrical wire screen 114, within but spaced from the walls of the

cylindrical casing 110. The cap-plate 113 is a closing end plate, but the cap plate 112 is provided with a central threaded opening for receiving a pipe 115. The water from the pipe 115 passes therefrom into the inside of the screen 114, thence outward through such screen to the outer passage of the cylinder, and thence through the water inlet passage 80 to the pump. The cap-plate 113 may have a removable plug 116, by the removal of which access is given to the interior of the screen 114, as for cleaning, without disturbing the clamping of the screen. The plug 116 is desirably eccentrically located, nearer the bottom than the top of the cap plate 113; to facilitate removal of any accumulation of dust within the screen 114. The two cap-plates 112 and 113 are interchangeable, to permit the pipe 115 to enter the casing 110 from either end.

I claim as my invention:

1. In combination, a turbo-pump having a vertical shaft, a single main anti-friction bearing supporting said shaft and located at the top thereof, a steady bearing near the lower end of the shaft, a steam turbine located between the two bearings and having a gland between it and each bearing, each gland being spaced from the adjacent bearing, and a multi-stage pump mounted on the shaft below the steady bearing.
2. In combination, a turbo-pump having a vertical shaft, a single main anti-friction bearing supporting said shaft and located at the top thereof, a steady bearing near the lower end of the shaft, a steam turbine located between the two bearings and having a gland between it and each bearing, each gland being spaced from the adjacent bearing, and a pump mounted on the shaft below the steady bearing.
3. In combination, a turbo-pump having a vertical shaft, a single main anti-friction bearing supporting said shaft and located at the top thereof, a steady bearing near the lower end of the shaft, a steam turbine located between the two bearings and having a gland between it and each bearing, each gland being spaced from the adjacent bearing, and a pump mounted on the shaft below the steady bearing, said pump having its inlet opening upward around the shaft below said steady bearing.
4. A turbo-pump, comprising a vertical shaft, a turbine rotor mounted on the upper part of said shaft, a turbine housing around said turbine rotor, a pump having one or more runners mounted on the lower end of said shaft and including a pump housing, and an intermediate housing mounted between the turbine housing and the pump housing and provided with a water-supply passage leading to the pump inlet.
5. A turbo-pump as set forth in claim 4, with the addition of a main bearing having

a housing mounted on top of the turbine housing, and a steady bearing mounted in said intermediate housing.

6. A turbo pump, comprising a vertical shaft, a turbine and a pump having their rotating parts carried by said shaft, a main anti-friction bearing carrying said shaft and located at the upper end thereof above both the turbine and the pump, a steady bearing 10 on said shaft at an intermediate point between the turbine and the pump, said bearings both being provided with jacket chambers, and conduits for supplying cooling fluid to said jacket chambers.

15 7. A turbo pump, comprising a vertical shaft, a turbine and a pump having their rotating parts carried by said shaft, a bearing carrying said shaft at the upper end thereof and located above both the turbine and the pump, a bearing on said shaft at an intermediate point between the turbine and the pump, said bearings both being provided with jacket chambers, and conduits for supplying cooling fluid to said jacket chambers.

20 25 In witness whereof, I have hereunto set my hand at Indianapolis, Indiana, this 6th day of January, A. D. one thousand nine hundred and twenty-seven.

VICTOR SCHLEYER.
